ALBERT A. WOOD,

Inventor,

By A. D. Wood
Atty.

UNITED STATES PATENT OFFICE.

ALBERT A. WOOD, OF ATLANTA, GEORGIA.

HOLLOW AUGER.

SPECIFICATION forming part of Letters Patent No. 690,338, dated December 31, 1901.

Application filed September 17, 1900. Serial No. 30,310. (No model.)

To all whom it may concern:

Be it known that I, ALBERT A. WOOD, a citizen of the United States of America, and a resident of Atlanta, in the county of Fulton and 5 State of Georgia, have made a certain new and useful Improvement in Hollow Augers; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

15 This device relates to tools for cutting tenons on the ends of wagon-spokes and the like by reducing their diameter, the invention consisting, primarily, in certain novel forms of mechanism for adjusting the cutting size, adjusting the knife whereby said cutting is accomplished, and in certain minor improvements in form and construction of the parts.

The device is shown in the accompanying drawings, in which—

25 Figure 1 is a side elevation of the auger. Fig. 2 is a face view thereof, and Fig. 3 a side elevation thereof in line with the edge of the cutting-knife. Fig. 4 is a view of the head, showing the adjusting-screw and sliding V-block, being in section on the line $x-x$, Fig. 2. Fig. 5 is section of Fig. 2 on the line $x-x$. Fig. 6 is a plan of the V-block, and Fig. 7 is an inverted plan view thereof, Fig. 8 being a view of the rear end. Fig. 9 is a side 30 view of the adjusting-screw.

In the figures like reference characters are uniformly employed in the designation of corresponding elements of construction in all the views.

40 A is the head; B, the shank-piece; C, the stop, and D the spindles. The construction of the three last-named parts—that is, the shank-pieces B, stop C, and spindles D—is immaterial to this device, as any form of construction for such parts will suffice for this 45 present description. The forms shown, however, follow the same parts as set forth in my application for Letters Patent for like device filed November 6, 1899, Serial No. 735,926, of 50 the series of 1880.

The head A is in the form of a circular face-

plate, finished on its face and edge and having a hole in its center the size of the maximum capacity of the auger. A radial (or otherwise) guideway a is provided in said face, and below said guideway, as best shown in Figs. 4 and 5, is a subrecess, preferably semicircular in form, the end wall of which recess is perforated and screw-threaded in said perforation to receive the lead-screw a', 55 which is provided near its head with an annular flange or subhead a², which fits against the bottom of the said subrecess and projects a portion into the aforesaid guideway. The V-block a³, the concave face of which forms 60 part of the wall of the central aperture and also forms two bearing-points for the tenon being cut, lies in the said guideway, fitting same and having movement radially of the central aperture therein. The under side of 65 the said V-block is provided with a notch or recess to fit the annular subhead a², which runs therein, and as said screw is screwed into and out of the screw-threaded perforation in the end wall of the subrecess this engagement of said annular subhead and the recess will cause a correlative movement of the V-block. A spring a⁴ is seated in the V-block a³, so as to bear upon the peripheral surface of the said subhead a², and by bearing forcibly thereon not only retard its otherwise free movement under the tremor of the V-block in working, but by pressing said subhead against the surface of the semicircular recess still further increases the friction there- 70 between, whereby this screw a' will under no circumstances "work" out. It is plain that to cut tenons truly cylindrical, reliable to size, and smooth this V-block must be stable in its adjustments—that is, it must remain where 75 it is set and not be permitted to spring back or recede from reliable contact with the two points on the tenon. This would be insured by a tight fit of the lead-screw thread were it practicable to make and keep such a condition in a screw-thread in so short a space. This being practically impossible I provide 80 rigidity of the screw by causing the annular flange or subhead to run and lie in contact with the bottom of the subrecess aforesaid, so 85 that any lateral thrust of the screw is resisted by a solid abutment, and the lead-screw is 90 95 100

completely housed in and protected from bending under strain in working and from accidental alteration of adjustment. The preferred form of construction of the V-block is to mill it from rectangular steel, and this consists in merely milling the V-face and guide-grooves, a pair of correlative ribs being milled in the sides of the depressed guideway. The formation of the guides and block might, however, be performed in many ways equally efficient.

A triangular notch is cut into the face-plate aforesaid and below this on the head A is formed a concave housing or web a^5 , extending from the back side of the face-plate to an inclined arm a^6 , the upper side of which arm forms the bearing and support for the knife and should be at such an angle to the face of the head A that the cutting edge of the knife will stand parallel to the face and at a proper distance above same. The cutting edge of the knife should also be parallel to the corner a^7 , Fig. 3; but this is merely a matter of grinding the knife to such angle that it will be so. The construction just described leaves an open space under the front half or third of the knife, so that chips have free exit and there is no danger of choking. The knife a^8 is a strip of steel beveled on its upper side and ends at such an angle that its edge has a little lead—that is, its cutting edge is projected higher above the face of the head A than any other part of it.

a^9 is the knife-cap, which is formed as shown in Figs. 1, 2, and 3, having a recess in its lower side for the knife, or, rather, to fit over the upper side of the knife and retain its proper relative position thereto, the ends of said cap being extended beyond said knife and its inner end being provided for the reception of the screw a^{10} , while its outer end is slotted to receive the screw a^{11} , both passing into the arm a^6 and serving to clamp the cap down firmly upon the knife. The hole 45 in the strap for the screw a^{11} is slotted, as shown, which permits the strap to pivot on the screw a^{10} . Therefore the knife, by reason of the recess in the strap, swings with the said strap and is thereby adjusted toward or 50 from the tenon. Other means than the groove in the strap might be employed to cause the knife and the strap to move together, but this form described is preferred; but it is found by practice that the tendency of the 55 knife and strap to swing on the pivoting-screw is greater than the tendency of the knife to slip back under the strap. I have therefore devised the following means to adjust with precision and hold the knife with 60 absolute rigidity against this tendency to swing by the force of and away from the work. From the lower side of the cap a^9 near its outer front corner projects a lug a^{12} , through which passes a set-screw a^{13} . A flat abutting surface for the screw a^9 is provided on the lug, as shown in Fig. 3. By means of this

construction an excessive tightening of the screws a^{10} and a^{11} is unnecessary, thus permitting the adjustment of the knife with reference to locating its inner corner to cut a 70 tenon the exact size of the opening after the longitudinal adjustment of the knife (to give the proper thickness of chip) shall have been made and the screws a^{10} and a^{11} sufficiently tightened. After the adjustment shall have 75 been made by the screw a^{13} the screw should be left in contact with its abutting surface, thus preventing the displacement of the knife by the strap swinging on the pivoting-screw a^{10} . It will be seen that each of these two 80 adjustments is independently made and secured.

Having thus described my invention, what I claim as new, and desire to secure by Letters Patent of the United States, is—

1. In a hollow auger, a head perforated and carrying a knife in cutting relation to said head, a substantially rectangular recess in the face of said head, a V-block slidably mounted in said recess and coincident to said perforation, a subrecess below said V-block with its bottom parallel to same and a lead-screw provided with an annular flange and screwed into the end wall of the said subrecess, said annular flange engaging said V-block and contacting with the bottom of the subrecess by the periphery of said flange.

2. In a hollow auger, a head perforated and carrying a knife in cutting relation to said head, a substantially rectangular recess in the face of said head, a V-block slidably mounted therein coincident with the said perforation, an extension of said recess downwardly in said head below said V-block with its bottom parallel to said V-block and a lead-screw screwed into the end wall of the last-named recess and adapted to engage said V-block, being for that purpose provided with a subhead and said V-block being notched to receive the said subhead, substantially as specified.

3. In a hollow auger, a head, perforated and carrying a knife in cutting relation to said head, a substantially rectangular recess in the face of said head, a V-block slidably mounted in said recess, an extension of said recess downwardly below said V-block and having its bottom parallel thereto, a lead-screw screwed into the end metal of said recess and adapted to engage the said V-block by its head and the said V-block being notched to receive said head and a spring seated in said V-block and adapted to bear one of its ends upon said screw-head.

4. In a hollow auger a head perforated and carrying a knife in cutting relation thereto, a guideway in said head below the face thereof, a V-block slidably mounted in said guideway, a recess in the lower side of said V-block and a hole drilled in said V-block forming a continuation of said recess, a recess in the said head below the guideway, a lead-

screw screwed into the end metal of said last-named recess and being provided with a sub-head adapted to engage the said V-block by the recess therein, and contact with the bottom of the recess in the head, and a spring seated in the aforesaid hole in the V-block and adapted to bear upon the periphery of the said subhead and press same against the

bottom of the said recess in the head, for the purpose specified. 10

In testimony whereof I hereunto affix my signature in presence of two witnesses.
